CIGARETTE KIT

Axel M. Walstrom, Minneapolis, Minn.

Application April 21, 1934, Serial No. 721,744

5 Claims. (Cl. 131—5)

My invention relates to cigarette forming devices which are designed to be carried about in a pocket of a person's clothes. The cigarette forming devices of this type, now in use, are comparatively bulky and of crude construction and appearance, and they also require considerable skill on the part of the operator in order to produce a satisfactory cigarette.

The object of my invention is to provide a more compact and efficient device which will fit neatly in a small sized vest pocket, and by which even an unskilled person can easily and quickly make a better cigarette.

Another object of my invention is to provide an improved cigarette forming mechanism by which cigarettes of different density, or firmness, as well as cigarettes of different size, in diameter, may be made as preferred, by any individual person.

20 A further object of my invention is to provide a cigarette forming mechanism by which the cigarette paper wrapper may be turned inwardly at each end to form crimped flanges which partially close both ends of the cigarette so as to prevent the loss of loose particles of tobacco at said ends.

25 A still further object of my invention is to provide such device with an interior compartment wherein a considerable number of cigarette papers may be conveniently carried, and from which single sheets of paper may be easily removed as required.

It is also an object of my invention to adapt such cigarette forming device to also serve as an attractive pocket cigarette case, or container, by providing a space therein which will conveniently accommodate several ready-made cigarettes.

30 My invention consists of the novel features which are described in the following specification, shown in the accompanying drawing, and specifically outlined in the annexed claims.

In the drawing:—

Fig. 1 shows an actual size end view of my invention, with its hinged cover in its closed position.

Fig. 2 shows a plan view of my invention, with its cover opened to display the interior of both cover and case.

35 Fig. 3 is an end view similar to Fig. 1, except that the device is tilted to its operative position, and this view shows the cover opened and a hinged section of the case swung upwardly into a position occupied while a cigarette is being formed.

Fig. 4 is a double size sectional view of the case portion of my device, showing the respective positions of its parts during the first step of the cigarette forming operations, and

Fig. 5 shows the function of said parts during the second step of the cigarette forming operations, while

Fig. 6 illustrates the final step of said cigarette forming operations.

Fig. 7 is a front view of the respective parts shown in Fig. 6, and

Fig. 8 is a perspective view of a cigarette having crimped ends, as produced with my invention.

The several views show how my invention is designed to form a compact pocket cigarette case, which is composed of parts A, B and C. Fig. 1 shows the case closed, as when taken from a pocket, while Fig. 3 shows it opened and tilted to the position in which it is held by the operator's left hand while a cigarette is being formed. When considered from the operator's viewpoint while in position shown in Figs. 2 and 3, the part A may be called the front part of the case and the part B may be called the rear part of the case, while the part C is the cover.

The part A has an upwardly curved front flange 10 and upwardly bent end flanges 11—11, while the part B has an upwardly curved rear flange 12 and upwardly bent end flanges 13—13. The end flanges 11 and 13 overlap and are hinged together at points 14—14, while the cover part C is hinged at 15 to the curved rear flange 12, as shown in Fig. 3, and a forwardly projecting tongue 16, on the part B extends under the front part A to hold said front part in normal alignment with said rear part B, as shown in Fig. 1.

A tubular front roll 17 is located within the part A near the curved flange 10, and the ends of said roll project through the end flanges 11—11 of said front part A, while a similar rear roll 18 is located within the part B near the curved flange 12, and has its ends projecting through the flanges 13—13. Knobs 19 and 20, preferably of resilient rubber, are secured to the projecting ends of the rolls 17 and 18, respectively, and these knobs have a rough surface to facilitate the rotation of said rolls by the thumb and first finger of the operator's right hand. A ribbon 21, of firmly woven fabric of comparatively light weight, has one end secured to the front roll 17, while its other end is secured to the rear roll 18, and this ribbon is of sufficient width to extend across the space between the end flanges 11—11 and 13—13 within the case, as shown in Fig. 2.

The ends of the ribbon 21 are wrapped about the rolls 17 and 18 in opposite directions and are secured to the rolls by being gripped between the over-lapped edges of the sheet metal strips from which said rolls are formed, as shown in Figs. 4, 5 and 6. The effective free length of the ribbon 21 between said rolls is approximately equal to twice the width of a standard size cigarette paper, and the outer surface of said ribbon is preferably coated with an elastic moisture-proof compound.

The cover C is preferably curved in cross-section, to make it rigid longitudinally while form-fitting transversely, and an inwardly curved outer edge 23 thereon is provided with a centrally located thumb-notch 24, and inwardly curved end flanges 25 thereon are provided with ears 26 which have indentations 27 adapted to snap over the slightly projecting pivot points 14-14 to 20 yieldingly secure said cover to the parts A and B, as shown in Fig. 1. The ears 26 extend inwardly from the end flanges 25 and have flat portions 28 which are spaced from the inside of the cover so as to overlap the outer ends of a loosely inserted retainer strip 29 which is preferably made of thin sheet celluloid and provided with a thumb notch 30 in one edge thereof. In this manner a pocket-like space is provided between the inside of the cover and the retainer strip 29, wherein 30 a considerable number of cigarette papers 31 may be carried, while the inwardly curved outer edge 23 prevents accidental displacement of said papers. The thumb notches 24 and 30 serve to facilitate the removal of single sheets of paper 35 as they are required, and I have found that plain papers, without a gummed edge, can be used successfully in my device.

The cover C is purposely made longer than the parts A and B, and extends beyond said parts 40 at both ends of the case, as shown in Fig. 2, so as to accommodate cigarette papers of usual length, while the width of the ribbon 21, and the space between the end flanges 11-11 and 13-13, is of less length than said papers, as also shown 45 in Fig. 2, so that the paper projects beyond said end flanges, as shown in Fig. 7, when said paper is inserted between the rolls 17 and 18. The end flanges 13-13, however, are provided with outwardly flared upper edges 32-32 which act to 50 turn the projecting ends of the paper 31 inwardly toward the center of the cigarette while it is being formed, (see Fig. 6), so as to partially close the ends of said cigarette, as shown in Fig. 8, for the purpose hereinafter described.

55 In operation:—

With my device held in the palm of the left hand, the cover opened, and the slack length of the ribbon 21 wound upon the front roll 17, the part A is then swung upwardly to the position 60 shown in Fig. 4, where it is supported by the thumb of the left hand, while the ribbon is depressed between the rolls by the first finger of the right hand to form a trough wherein a desired quantity of loose tobacco 33 is poured from 65 a tin or pouch held in the right hand. When this tobacco is levelled in the trough by the first finger of the right hand, the part A is moved, by the thumb of the left hand, to a point where the rolls 17 and 18 are very close together, as 70 shown in Fig. 5, where the parts A and B are then yieldingly pressed together by the thumb and fingers of the left hand, while the thumb and first finger of the right hand rotates the knob 20, in the clock-wise direction indicated by 75 the large arrow in Fig. 5, to wind the ribbon onto

the rear roll 18. This rotating operation causes the ribbon to travel from the roll 17 to the roll 18, while it acts to roll the tobacco 33 into a compact cylindrical form beneath the rolls, as shown in Fig. 5. At the end of this tobacco rolling movement of the ribbon, the rolls are separated slightly and the lower edge of a cigarette paper is then inserted between said rolls into contact with the tobacco therein, and then said rolls are moved close together again. Now, as 10 the paper is slightly longer than the parts A and B, the ends of said paper will project slightly at each end of said parts, so that when the rolls are moved close together again, the flared edges 32-32 will cause the ends at the lower edge of 15 said paper to be turned inwardly, and these inwardly turned ends will be crimped over the ends of the cylindrical roll of tobacco therein, by frictional contact with the inner surface of the end flanges 11-11 and 13-13, so as to form an in- 20 wardly extending paper flange at each end of the cigarette while the roll 17 is rotated in an anti-clockwise direction, which causes said ribbon to travel in the direction indicated by the arrows in Fig. 6. Now, when this latter rotation of the 25 knob 19 has drawn the paper about the roll of tobacco to a point where the upper edge of said paper projects slightly above the rolls, as shown in Fig. 6, the operator halts the movement of the ribbon momentarily while he moistens the projecting edge of the paper with saliva from the tip of his tongue, and then completes the rotation of the roll 17 to the end of the movement of said ribbon. When the rolls are again separated, a perfectly formed cigarette will be exposed on the 35 top of the ribbon, and this cigarette will have partially sealed ends, as shown in Fig. 8, which eliminates the now common practice of twisting said ends to prevent loss of certain kinds of finely flaked tobacco, while it also prevents loose particles of tobacco from entering the mouth of the 40 smoker.

As the knobs 19 and 20 are preferably of slightly larger diameter than the rolls 17 and 18, said knobs will contact each other during 45 the cigarette forming operations, and, as they pass in opposite directions at the point of contact, although rotating in the same direction, a frictional engagement between them, at said point of contact, will cause a tension in the ribbon 50 21, which acts to increase the firmness and density of the cigarette in proportion to the degree of pressure exerted on the parts A and B by the thumb and fingers of the left hand. The thickness or diameter of the cigarette is deter- 55 mined by the amount of tobacco placed in the trough of the ribbon, and, as the ribbon of my device is free to accommodate itself to whatever amount of tobacco is preferred, a very thick cigarette is as easily formed as a very thin one. 60 This important feature is not found in the devices now in general use, in which the cloth ribbon used is of a predetermined length designed to produce a cigarette of a certain diameter, and by which a very tightly packed cigarette results 65 if too much tobacco is used, or, a very loosely packed cigarette results if not enough tobacco is used. With my device, however, the density of the cigarette is determined altogether by the friction produced between the knobs 19 and 20, 70 which, in turn, is controlled by the degree of pressure exerted on the parts A and B by the thumb and fingers of the left hand, as before mentioned. The friction between the knobs 19 and 20 tends to tighten or stretch the ribbon 21 75

between the rolls 17 and 18, and thus serves to exert more pressure on the tobacco which is being rolled into cylindrical form by said ribbon.

From the foregoing description, it will be evident that I have devised a novel combination cigarette case and forming device having many meritorious features which are concisely pointed out in the following claims.

I claim:—

10. 1. A cigarette making device comprising: a case composed of two sections hinged edge to edge and having upwardly turned end flanges, a roll mounted along the outer edge in the first section and a second roll mounted along the outer edge in the second section and the ends of said rolls projecting through the end flanges of said sections, a flexible ribbon having one end attached to the first mentioned roll and its other end attached to the second roll and said ribbon being as wide as the space between the end flanges of said sections and round knobs provided on the projecting ends of said rolls on the same side of the case, said knobs adapted to be moved into frictional engagement with each other so as to create a tension in said ribbon during the cigarette forming operation substantially as described.

2. A cigarette making device comprising: a case composed of two sections hinged together and having upwardly turned end flanges, a roll mounted along the outer edge in the first section and a second roll mounted along the outer edge in the second section, the ends of said rolls projecting through the end flanges of said sections and said rolls adapted to be moved close together in parallel relation when said sections are folded, a flexible ribbon having one end attached to the first mentioned roll and its other end attached to the second roll and said ribbon being as wide as the space between the end flanges of said sections, round knobs provided on the projecting ends of said rolls on the same side of the case, said knobs being adapted to be moved into frictional engagement with each other when said sections are folded, and a cover hinged to the outer edge of the second section, said cover being of sufficient width to extend over both of the sections when said sections are in their opened position substantially as described.

3. In a cigarette making device, a shallow rectangular box composed of a pair of frames normally disposed in relatively level formation when in an inoperative position and pivotally connected at points substantially coinciding with the longitudinal center-line of said box and said

frames having flat panels which normally combine to form a substantially flat bottom in said box while the panel of one of said frames extends beneath the panel of the other frame so as to normally support said other frame in its 5 relatively level position, and means provided in said box for the purpose of forming a cigarette therein when said frames are folded into operative position substantially as described.

4. A cigarette making device comprising, a 10 shallow rectangular box composed of a pair of frames normally disposed in relatively level formation and pivotally connected at points substantially coinciding with the longitudinal center-line of said box and said frames having 15 flat panels which normally combine to form a substantially flat bottom in said box, a roll disposed along the outer edge in one of said frames and another roll disposed along the outer edge in the other frame and said rolls being journaled 20 in the ends of said frames and spaced far apart in said box, a flexible ribbon having one end attached to one of said rolls and its other end attached to the other roll and said ribbon being of sufficient width to extend from one end to 25 the other end in said box and adapted to form a shallow trough between said rolls wherein several ready-made cigarettes may be stored side by side in a single tier, a lid hinged at the outer edge of one of said frames and adapted to 30 extend over both of said relatively level frames to normally cover said box and the cigarettes in said trough, and knobs provided at the outer ends of said rolls for the purpose specified.

5. A cigarette forming device, comprising, a 35 pair of pivotally connected frames, a pair of parallel rolls normally spaced apart in said frames and having projecting ends on the same side of the frames, a flexible ribbon extending from one of said rolls to the other roll and having its ends wrapped about said rolls in opposite direction and secured to said rolls, said ribbon adapted to be depressed to form a trough between said spaced rolls and said rolls adapted to be moved close together in parallel relation 40 so as to cause said trough to assume a cylindrical form beneath said rolls, and suitable knobs provided on the projecting ends of said rolls adapted to be moved into frictional engagement with each other when said rolls are moved near 45 together, said knobs being adapted to serve as finger-grips for alternately rotating said rolls so as to wind said ribbon about one roll while unwinding from the other roll substantially as 50 described.
